SIGN PROJECTION APPARATUS

Maurice H. Goldberg, Chicago, Ill.

Application July 27, 1936, Serial No. 92,866

4 Claims. (Cl. 88—28)

This invention relates to projection apparatus in general, and more particularly to an improved sign projection apparatus adapted for use for advertising purposes by projecting words or symbols on a screen or other plain surface, the image of these words or symbols traveling across the surface of the screen at a constant predetermined rate of speed, so that long messages may be exhibited.

10 It is the main object of this invention to produce an improved sign of the image projection type whereby a continuous moving series of advertisements may be displayed upon any plain surface, the device including a relatively large 15 film aperture, whereby several words of a message may be projected, thereby eliminating excessive enlargement.

Another object of the invention is to provide an improved sign of the image projection type 20 which will produce a continuous moving series of advertisements to be read horizontally, said images being capable of display on any surface having ordinary reflecting properties.

Another object of the invention is to produce 25 an improved sign of the image projection type in which a continuous loop film is employed, novel and improved means for housing said film, and means associated with said housing means for adjusting the desired length of film to be used.

30 A still further object of the invention is to provide an improved sign of the image projection type which will be compact in size, cheap and simple of operation, and which will be at the same time highly efficient for carrying out 35 the purposes for which it is designed.

With the foregoing and other objects in view which will appear as the description proceeds, the invention consists in certain novel features of construction, arrangement and combination of 40 parts hereinafter fully described, illustrated in the accompanying drawing, and particularly pointed out in the appended claims, it being understood that various changes in the form, proportion, size and minor details of the structure 45 may be made without departing from the spirit or sacrificing any of the advantages of the invention.

For the purpose of facilitating an understanding of my invention, I have illustrated in the 50 accompanying drawing a preferred embodiment thereof, from an inspection of which when considered in connection with the following description, my invention, its mode of construction, assembly and operation, and many of its advan-

tages should be readily understood and appreciated.

Referring to the drawing in which the same characters of reference are employed to indicate corresponding or similar parts throughout the 5 several figures of the drawing:

Figure 1 is a top plan view of my improved sign projection apparatus, the cover being removed therefrom;

Fig. 2 is a front elevational view of the same; 10

Fig. 3 is a sectional view taken substantially on line 3—3 of Fig. 2;

Fig. 4 is a sectional view taken substantially on line 4—4 of Fig. 1; and

Fig. 5 is a sectional view taken substantially 15 on line 5—5 of Fig. 1.

Stated generally, the invention consists of a conventional stereopticon projecting and condensing lens and light box combined with a novel construction of housing for receiving an endless 20 film, means for actuating said film, and means whereby the length of film used may be varied. The words or symbols appearing on the character bearing element or film may be projected 25 on any surface having reflecting properties at a constant predetermined rate of speed, so that long messages may be displayed or exhibited without necessitating excessive enlargement.

Referring to the drawing more specifically by 30 characters of reference, the numeral 10 designates a housing within which is mounted a light source 11, reflector 12 and condensing lenses 13. Attached to said housing is a substantially rectangular film carrying housing 14, which is attached to said housing 10 by means of suitable 35 screws extending through brackets or projections 16 provided on the housing 14, the latter being secured to the housing 10 to the front and rear walls thereof. The housing 14 is thus suitably spaced from the housing 10 so as to protect the film disposed therein from the heat created by the light source 11 in the housing 10.

The housing 14 is provided with a cover member 15 which is fastened in place in any suitable manner when the device is in fully assembled position. The housing 14 is adapted to enclose a character bearing element or film 17, which in the present instance is made of material such as that found in motion picture films, and is made in an endless ring or band form, as shown 40 in the drawing.

Adjacent the forward end of the housing 14 is provided a substantially rectangular shaped member 18 having a rectangular aperture 19 45 provided therein, which aperture is in alignment 50 with the drawing.

with an opening 20 provided in the housing 10 and to the rear of which opening are mounted the condensing lenses 13. The opening 19 provided in the frame 18 is relatively long, so that 5 several words or messages to be read may be projected therethrough, thereby eliminating excessive enlargement.

Disposed in front of said film opening 19 is a 10 suitably hinged member 21 which is normally held in closed position, as shown in Fig. 3, by means of a spring 22, said member 21 being effective for maintaining the film 17 in a substantially vertical position as it passes along said opening. Extending forwardly from said member 15 18 are a pair of hollow members 23 and 24 within which are telescopically mounted rods 25 and 26, to the free ends of which rods is secured a frame member 27 carrying a projecting lens 28. The lens 28 may be adjusted towards and 20 away from the film opening by means of adjustable screws 29 (Figs. 1 and 4).

In the forward ends of the housing 14 are 25 rotatably mounted a pair of rollers 30 and 31, between which rollers the film 17 is stretched across the field of the lenses 13 and 28. From the roller 31 the film extends rearwardly and passes around a roller 32, then forwardly and around a roller 33, then rearwardly again around a roller 34. From the roller 34, the film extends 30 across the rear end of the housing 14 around a roller 35, then forwardly to a roller 36, then rearwardly again to a roller 37, and then forwardly again around the roller 30. The roller 32 is mounted within an elongated slot 38 (Fig. 1) 35 provided in the bottom wall of one side of the housing 14, whereby the said roller may be adjusted along said slot to vary the tension on the film and also to permit the disposition within said housing of films of varying lengths. The 40 length of film may also be varied by eliminating the roller 37, for example, in which case the film would pass from the roller 36 directly to the roller 30. All of said rollers may be mounted upon pins secured to the bottom wall of the 45 housing 14, or in some other suitable and well known manner.

To actuate said film 17, the roller 31 is provided with suitable teeth 39 which are received within projections (not shown) provided adjacent the top and bottom of the film 17. The roller 31 is connected to a shaft 40 which is driven by a motor 41.

To secure sufficient friction between the film 17 and the driving roller 31, I provide a friction 55 roller 42 (Figs. 1 and 5) which is eccentrically mounted on a stud 43 extending through an opening in the bottom wall of the housing 14. A suitable wing nut 44 may be used for securing the roller 42 in adjusted position.

60 The operation of the device is as follows: The motor 41 is supplied with current from any suitable source, and the lamp 11 is energized so that it throws a beam of light through the condensing lenses 13. The motor drives the shaft 40 which 65 in turn drives the roller 31, thereby moving the film 17 with the various words and symbols provided thereon past the aperture 20. As a result, the image of the words or symbols on the film is thrown against the screen, these images traveling across the screen from right to left at a slow rate of speed, so that new words or symbols are constantly appearing on the 70 screen.

75 It will be noted that the device is so constructed that the same is highly useful for ad-

vertising purposes, and is capable of being set up in such a position that it can throw its image on a screen or plain wall located in a position where it can be seen by the public. It will also be noted that the device is simply constructed, compact, and when once set in operation, will operate with very little attention.

It will further be noted that the housing 14 carrying the film 17 is so arranged with reference to the housing 10 carrying the light 11 that it is completely insulated therefrom, thereby preventing damage to the film by reason of excessive heat. This insulative feature is also due in part to the fact that the housing 14 completely surrounds and encloses the film 17, which further results in weather-proof protection of the film to adapt the device to outside use. It will also be noted that the film may be readily inserted and removed from the housing 14 and that the length of film may be varied by merely adjusting the roller 32.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A device of the character described comprising a housing carrying a light source and a condensing lens, a projecting lens disposed in front of said housing, a substantially U-shaped trough-like member surrounding said housing in spaced relationship thereto, an endless film having characters provided thereon running lengthwise thereof disposed within said trough-like member, rollers in the forward ends of said trough-like member adapted to have the film stretched therebetween through the field of said lenses, a plurality of other rollers positioned within said trough-like member adapted to have a portion of said film stretched therebetween, means for actuating said film, and a removable cover for said trough-like member, whereby said film is effectively protected and is insulated from heat generated by said light source.

2. A device of the character described comprising a housing carrying a light source and a condensing lens, a projecting lens disposed in front of said housing, a substantially U-shaped trough-like member surrounding said housing in spaced relationship thereto, an endless film having characters provided thereon running lengthwise thereof disposed within said trough-like member, rollers in the forward ends of said trough-like member adapted to have the film stretched therebetween through the field of said lenses, a plurality of other rollers positioned within said trough-like member adapted to have a portion of said film stretched therebetween, means for actuating said film, one of said last mentioned rollers being adjustably mounted in a slot in said trough-like member, whereby the tension on said film may be varied, and a removable cover for said trough-like member, whereby said film is effectively protected and is insulated from heat generated by said light source.

3. In a projection apparatus, a housing carrying a light source and a condensing lens, a projecting lens disposed in front of said housing in

optical alignment with said light source and said condensing lens, a substantially U-shaped, hollow housing mounted upon and extending substantially around said first housing and air-separated therefrom, an endless film disposed within said U-shaped housing and extending between said condensing lens and said projecting lens, and means for moving said film therewith, whereby free circulation of air over and between said housings is obtained by natural draft so that said film is effectively protected and is insulated from heat generated by said light source.

4. In a projection apparatus, a housing carrying a light source and a condensing lens, a projecting lens disposed in front of said housing in optical alignment with said light source and said condensing lens, a substantially U-shaped, hollow housing surrounding said first housing in spaced relationship thereto, an endless film dis-

posed within said U-shaped housing and extending between said condensing lens and said projecting lens, whereby said film is effectively protected and is insulated from heat generated by said light source by said U-shaped housing, a frame member mounted at the front of said first housing between the end portions of said U-shaped housing having an aperture in optical alignment with said light source and said lenses through which said film extends, means for moving said film through said aperture, a second frame member pivotally mounted on said first frame member having an aperture therein adapted to substantially coincide with said first aperture, and spring means for resiliently maintaining said frame members in contact with each other to maintain said film in proper position in the field of said lenses.

MAURICE H. GOLDBERG.
